United States Patent

Des. 234,538

Patented Mar. 18, 1975

234,538

PORTABLE RADIO

Takeyoshi Kawano, Kyoto, and Hiroshi Hirasa, Osaka, Japan, assignors to Matsushita Electric Industrial Co., Ltd., Osaka, Japan

Filed Aug. 22, 1973, Ser. No. 390,636

Claims priority, application Japan Apr. 11, 1973

Term of patent 14 years

Int. Cl. D14—03

U.S. Cl. D56—4 B

FIG. 1

FIG. 2

FIG. 1 is a front, top and right side perspective view of a portable radio, showing our new design;

FIG. 2 is a rear, bottom and left side perspective view.

Portions of the drawing figures are shaded to indicate contrast in appearance, and a portion of FIG. 1 has been diagonally lined to indicate transparency.

We claim:

The ornamental design for a portable radio, as shown and described.
